UNITED STATES PATENT OFFICE.

IVON S. PIETERS, OF CHICAGO, ILLINOIS, ASSIGNOR TO PLIBRICO JOINTLESS FIRE-
BRICK COMPANY, OF CHICAGO, ILLINOIS, A CORPORATION OF ILLINOIS.

FURNACE.

Application filed November 9, 1925. Serial No. 67,844.

This invention relates to furnaces, more particularly to an improved furnace construction having particular utility under oil refining stills and the like, and its objects 5 are the provision of a generally improved furnace construction and setting that will better serve the purpose for which intended, particularly in connection with stills and the like.

10 The invention is illustrated in the accompanying drawings, in which

Fig. 1 is a vertical longitudinal sectional view of an embodiment of the invention, taken on the line 1—1 of Fig. 2 and showing 15 in elevation the shell or drum of the still illustrated therewith;

Fig. 2 is a transverse vertical section taken on the line 2—2 of Fig. 1; and

Fig. 3 is an enlarged front elevational 20 view of the fire door or cover showing the particular burner connections selected for illustration.

The setting shown in the drawings comprises the longitudinal side walls 5, rear 25 wall 6 and front wall 7. These walls may be formed of common brick blocks which may be laid up and bonded together in the usual or any suitable manner.

The bases of the walls 5 may be wider 30 or set in to form horizontal shoulders 8 longitudinally along the interior of each wall 5 adjacent its base portion and the bottom 9 of the furnace may comprise the desired number of courses of common brick 35 blocks laid horizontally across the shoulders 8 and extending longitudinally through the furnace from the front wall 7 to the bridge wall 10. The upper ends of each of the walls 6 and 7 may be provided with suitable de-

pressions 12 for receiving the opposite ends 40 of the still, shell or drum 14, suitable packing or yieldable seating material, such as asbestos rope, being preferably employed at 16 to allow for the expansion and contraction which occurs.

An underlying column 17 may be disposed beneath the still 14 at the front and substantially centrally between the opposite side walls 6 and 7. The column 17 may be formed of fire brick blocks suitably laid up with a packing or yieldable seating material, such as, for instance, rope again interposed at 18 between the top of the column 17 and the bottom of the still 14. The still connection 19 is shown as passing 45 through the front wall 7 of the setting.

The bottom of the furnace chamber 20 has two fire boxes or tunnels 21, 21 one extending longitudinally along each side wall 5 from the front wall 7 to the bridge wall 10. The interior of the furnace is preferably 50 provided with a monolithic refractory lining 23 installed in plastic condition, and the tunnels 21, 21 are also preferably of the same material, thereby affording a one-piece jointless lining and tunnel formation within 55 the furnace. The bottom of the furnace chamber 20 may have a course 24 of fire brick laid upon the courses 9 between the tunnels 21, 21 and the interior of the tunnels 21 may similarly have bottom courses 25 of 60 fire brick laid upon the courses 9 through the entire interior of the tunnels 21. The bridge wall 10 is also preferably formed of the same monolithic refractory material. The monolithic lining 23 may be bonded to 65 the walls of the furnace fitting where desired by anchors 28.

The tunnels or "dog houses" are in this instance fired by oil burners 30, 30, one for each of the tunnels 21. Natural gas or any 70 other suitable or preferred fuel may of course be employed. These burners 30, which may be of any suitable or preferred form, may be mounted in the fire openings 32, one opening through the front wall 7 75 into each of the tunnels 21. Each burner 30 may include a suitable nozzle 34 disposed to emit the heating flames into the tunnel 21. Fuel oil for each burner 30 may be delivered to the same by means of a conduit 35, while 80 a second conduit 36 may deliver steam or air, as desired. Each fire box or tunnel cover or door 38 may be provided with suitable controllable air ports and damper means and atomizing and carburetor means may be 85 provided for the burners, as desired.

The tops of the tunnels 21 are flat and have suitable openings 40 which form vents and also provide for regulating the operation of the furnace as well as for securing uniform operating temperatures. The openings 40 may be covered by ordinary fire brick blocks 42 laid loosely upon the top of the tunnel. The openings 40 may be closed entirely by the bricks 42, thereby closing off 90 communication between the interior of the tunnels 21 and the furnace chamber 20 through the tops of the tunnels entirely, or the blocks 42 may be spaced apart or some 95 may be removed to vary the area of the 100 top of the tunnel.

105 110

openings 40 and obtain the most suitable draft conditions. The stack damper (not shown) may, of course, provide further control.

- 5 The inner wall 45 of each tunnel 21 has a plurality of flame openings 46 opening into the furnace chamber 20 horizontally therethrough so that the flames, instead of impinging directly upon the still 14, are directed horizontally or laterally into the furnace chamber 20. In this manner an even distribution of the heat to the bottom of the still is secured and excessive or overheating and undesirable flame impingement 10 upon the bottom of the still are prevented. The bricks 42 for closing and controlling the opening 40 through the tops of the tunnels 21, may be supported on the spaced arch-like tops 48 of the tunnels 21. The directing of the flames from the two tunnels toward each other, also tends to assure more completely burning of any fuel particles carried into the furnace chamber and this increases the efficiency.
- 15 25 From the foregoing, it will now be apparent that the tunnels form fire or combustion chambers along the opposite sides of the interior of the furnace from the front wall 7 to the bridge wall 10. In operation, the flames issue from the burners 30 into the tunnels 21. These flames traversing the tunnels 21 issue laterally through the openings 46 and heat the interior of the furnace chamber and the still uniformly and without direct flame impingement upon the still.

The still 14 may be supported or suspended from overhead supports (not shown) with its ends merely fitting in the front and rear walls 7 and 6. In this way the setting walls 40 may be relieved of the weight of the still.

In the drawings, the vertical breech passage is designated at 60 and the bottom of this passage opens into the rear end of a horizontal tunnel or conduit 62 through 45 which the products of combustion may pass out from the furnace. The front wall 7 is provided with a suitable air admission opening 63 which may have a controllable door 64 and by connecting the outer end of the conduit 62 with the opening 63 by means of a suitable conduit 65, as shown in dotted lines in Fig. 1, the products of combustion passing out through the tunnel 62 may be re-delivered back into the furnace chamber 20. A re-generative or re-circulating system for the products of combustion is thus provided.

It is to be understood that the products of combustion will be drawn or forced out 60 through the conduit 62 by suitable fan or impeller means, which may be of the suction or force type, providing a suction or forced draft system as desired.

The tunnel 62 may comprise a double pas- 65 saged conduit, as shown, laid horizontally

beneath the bottom courses 9 and substantially centrally between the side walls 5 with its inner end opening into the passage 60 and its outer end opening out from the front. The spaces between the sides of the tunnel 70 or conduit 62 and the walls 5 may be filled in with earth or other suitable filling material.

I do not intend to be limited to the precise details shown or described. 75

I claim:—

1. In combination, a furnace setting having an internal chamber, a still shell exposed to said chamber, and a pair of fire boxes disposed within said chamber and having side walls provided with openings into the furnace chamber therethrough for directing the flames from said fire boxes against each other and into said internal chamber without direct impingement upon the still shell. 80

2. In combination, a furnace setting having an internal chamber, a still shell exposed to said chamber, and a pair of fire boxes disposed within said chamber and having side walls provided with openings into the furnace chamber therethrough for directing the flames from said fire boxes against each other and into said internal chamber without direct impingement upon the still shell, 85 said fire boxes having tops provided with openings into the furnace chamber and means for controlling said top openings. 90

3. In combination, a still, an underlying furnace setting, said setting having a furnace chamber, and a pair of fire boxes extending longitudinally along opposite sides of said chamber and having side outlets opening toward each other and into the furnace chamber for directing the flames from said fire boxes against each other and into 100 said internal chamber without direct impingement upon the still shell. 105

4. In combination, a still, an underlying furnace setting, said setting having a furnace chamber, a pair of fire boxes extending 110 longitudinally along opposite sides of said chamber and having side outlets opening into the furnace chamber for directing the flames from said fire boxes against each other and into said internal chamber without direct impingement upon the still shell, 115 said fire boxes having tops provided with openings into the furnace chamber and blocks laid upon the tops of said boxes for closing said openings and separable to open 120 same and vary the area of opening.

5. In combination, a furnace setting having front, rear and side walls, a still supported over said setting, a bridge wall spaced from the rear wall and forming a passage 125 therebetween, a pair of fire boxes extending longitudinally along opposite sides of the interior of the setting and having side outlets opening into the setting for directing the flames from said fire boxes against each 130

other and into said internal chamber without direct impingement upon the still shell, and a horizontal tunnel underlying the bottom of the setting, said tunnel opening at 5 its rear into the bottom of said passage and at its opposite end out through the front. 6. In combination, a furnace setting having front, rear and side walls, a still supported over said setting, a bridge wall 10 spaced from the rear wall and forming a passage therebetween, a pair of fire boxes extending longitudinally along opposite sides of the interior of the setting and having side outlets opening into the setting for direct- 15 ing the flames from said fire boxes against each other and into said internal chamber without direct impingement upon the still shell, a horizontal tunnel underlying the bottom of the setting, said tunnel opening at 20 its rear into the bottom of said passage and at its opposite end out through the front, the front wall having an inlet opening, and conduit means connecting said tunnel with said inlet opening for redelivering the products 25 of combustion into the interior of the setting.

7. In combination, a furnace setting having an internal furnace chamber and open at the top, a still shell mounted upon the top of said setting and exposed directly to the internal chamber of said setting through the 30 open top thereof, a fire box disposed within said setting, means for firing the fire box internally, said fire box having side outlets opening into the chamber and directed away from the portion of the shell exposed internally to said chamber to direct the heat and flames from the fire box into the chamber of the setting without direct impingement upon said shell, means other than the side outlet 35 from said fire box for conveying the products of combustion from said chamber, said fire box having its top disposed within the furnace chamber and provided with openings into said chamber and blocks laid upon the top of the fire box for closing said openings and separable to open same and to vary the amount of opening. 40

In witness whereof, I hereunto subscribe my name this 3rd day of November, 1925.

IVON S. PIETERS.
